Frank A. Cutler, ATTORNEY.

UNITED STATES PATENT OFFICE.

CARL L. ERICSON, OF LONGMEADOW, AND WILLIAM ROBERTS, OF SPRINGFIELD, MASSACHUSETTS; SAID ERICSON ASSIGNOR TO AMERICAN SAW AND MANUFACTURING COMPANY, OF SPRINGFIELD, MASSACHUSETTS, A CORPORATION OF MASSACHUSETTS.

RATCHET WRENCH.

Application filed September 18, 1924. Serial No. 738,429.

To all whom it may concern:

Be it known that we, CARL L. ERICSON, a subject of the King of Sweden, residing at Longmeadow, in the county of Hampden and State of Massachusetts, and WILLIAM ROBERTS, a citizen of the United States of America, residing at Springfield, in the county of Hampden and State of Massachusetts, have jointly invented a new and useful Ratchet Wrench, of which the following is a specification.

Our invention relates to improvements in tools commonly known as ratchet wrenches, with which members, parts, or objects to which the same are applied may be rotated by a step-by-step movement in either direction; and consists essentially of a perforated head having extensions or lugs with a space between, a center piece or work-holder loosely arranged in the perforation or opening in said head, means to retain said work-holder in said opening, and an operating handle pivotally connected with said lugs and adapted to have one terminal oscillated in said space, said handle at said terminal having a cam-surface to engage and grip the periphery of said work-holder, when said handle is swung on its pivot in either direction, or alternately to grip and release said periphery as said handle is swung to and fro within certain limits less than the maximum limits of the movement of the handle, all as hereinafter set forth.

The primary object of our invention is to produce a reversible ratchet wrench which, while possessing the strength, durability, and other characteristics essential to such a wrench, is extremely simple in construction and operation, and can be manufactured at a minimum cost. This wrench comprises few parts which can be easily and quickly assembled.

Another object is to provide a wrench of this character with simple and inexpensive means for holding the central, rotatable member against movement longitudinally on its axis.

Other objects and advantages will appear in the course of the following description.

We attain the objects and secure the advantages of our invention by the means il-

lustrated in the accompanying drawings, in which—

Figure 1 is a top plan of a ratchet wrench which embodies a practical form of our invention; Fig. 2, a central vertical section through said wrench, taken on lines 2—2 in Fig. 1; Fig. 3, a central vertical section through a ratchet wrench which is provided with modified means for retaining the central member in place in the head; Fig. 4, a central vertical section through a ratchet wrench which embodies still another modification of the holding or retaining means for the central member; Fig. 5, a sectional view generally similar to Fig. 2, except that the wrench is equipped with friction engaging means for the object to which said wrench is applied; Fig. 6, a horizontal section through a portion of the wrench shown in Fig. 3, said section being taken on lines 6—6 in that view; and Fig. 7, a horizontal section through the wrench shown in the first two views, said last-named section being taken on lines 7—7 in Fig. 2.

Similar reference characters designate similar parts throughout the several views.

In Fig. 1 the handle of the wrench is shown in neutral position in full lines, and in one of its operative or active positions by dot-and-dash lines. In each of Figs. 3, 4, 5, and 7 only the inner-end portion of the handle is shown, and the same is in neutral position.

This ratchet wrench, in each example, comprises a head 1 having therein a central opening 3 that extends through from side to side or top to bottom, and being provided with a pair of lugs 4 between which is a space 5; a center piece or work-holder 8 that is adapted to receive or engage the work, and here is approximately of the same thickness as said head and fits said opening, said head and work-holder normally being independently rotatable, and said work-holder having, in each of the present examples, an angular opening 9 therein to receive the object to be rotated, such opening extending through the work-holder from side to side or top to bottom; means to retain said work-holder in the opening therein, which means will subsequently be described; and an

operating handle 10 that has its inner terminal portion inserted in said space 5 and pivotally connected at 11 with said lugs, the inner end of such terminal portion being 5 convex to form a cam surface 12.

Some portion of the periphery of the work-holder 8 extends into or is exposed through the space 5 in position to be engaged by the cam-surface 12, which cam-surface is 10 on an arc of a circle whose center is back of the axis of the pivot 11, slightly toward the free end of the handle. When the handle 10 is disposed with the axis of the handle 10 and centers of cam-surface 12 and work-holder 15 8 substantially in line, said cam-surface is out of contact with the adjacent portion of the work-holder 8; but, when said handle is swung on the pivot 11 in either direction, 20 said cam-surface is caused to contact with said work-holder and exerts pressure thereon in proportion to the force exerted on the handle, with the result that said work-holder and the head 1 are locked together and carried with the handle in the direction 25 in which the same is being moved. The foregoing is true because the distance between the center of the pivot 11 and either 30 end of the arc of the cam-surface is greater than the distance between said center and any point in such arc which is intermediate of its ends, or, in any event, sufficient to cause said cam-surface to grip and carry with it the work-holder 8, when the handle 10 is swung in either direction on said pivot.

35 As a simple and inexpensive means of retaining the work-holder 8 in the opening 3, we may form an annular groove 13 in the center of the periphery of said work-holder, and insert a radial pin 14 through the periphery of the head 1 and into said groove. The pin 14 has a tight fit in the head 1, but a loose fit in the groove 13 so as not to interfere with the rotation of the work-holder 8 in said head or the latter on the former—see Figs. 1, 2, and 7. In this case 40 the thickness of the cam-surface 12 and the diameter of the pin 14 are substantially the same, and said cam-surface is received in the groove 13 and engages the inner side of 45 said groove. Thus it is seen that the inner terminal portion of the handle 10 assists in retaining the work-holder 8 in place in the head 1.

Instead of providing the pin 14 to prevent or assist in preventing the work-holder 55 8 from slipping out of the opening 3, we may provide the head 1 with an integral lug 15 which enters the groove 13, as shown in Figs 3 and 6. In order to produce the lug 60 15, a slot 16 is milled or otherwise formed in the periphery of the head 1 to thin the metal of said head at some point adjacent to the groove 13, and such thinned portion is then forced inwardly between the top and 65 bottom sides of said groove. The width of

the slot 16 corresponds with that of the groove 13. Here, again, the inner terminal portion of the handle 7 assists in holding the work-holder in place.

Still another modification of the retaining means for the work-holder 8 is illustrated in Fig. 4. Here there are no grooves or slots or openings in the peripheries of the head 1 and work-holder 8, but the latter is originally made a little thicker than the former, and the top and bottom sides of the same are upset, as shown at 17, to form flanges that engage the edge portions of the opening 3. Each of such edge portions may be machined off on a bevel, if necessary, to provide seats for the upset parts or flanges 17 of the work-holder. After the work-holder 8 in this example has been upset at both ends, the same is approximately of the same thickness as is the head 1 in which said work-holder is located. There being no groove in this work-holder, the cam surface 12 does not penetrate or pass inwardly beyond the major periphery of said work-holder.

If it be desired to provide any one of these ratchet wrenches with friction-engaging means for the object operated on by the wrench, a spring-pressed ball 18 may be introduced into the construction. In such case a radial opening or passage 19 is drilled in the work-holder 8, the drill being stopped after its point enters the opening 9, and before the major diameter of the drill passes into said opening. A seat at the inner end of the passage 19 is thus produced for the ball 8, which seat allows a portion of said ball to project into the opening 9. A spring 20 is inserted in the passage 19 between the ball 18 and that part of the head 1 which closes said passage at the outer end. The spring 20 normally retains the ball 18 on its seat at the inner end of the passage 19, but yields when an object, which is of a size generally corresponding with that of the opening 9, passes through said opening. The spring 20, however, forces the ball 18 against that part of the object which is in the opening 9, and the wrench is thereby prevented from slipping down on said object, or, in any event, a better engagement between the work-holder 8 and the object is afforded, such engagement being of a nature that facilitates the 110 operation of the wrench in rotating the object in either direction.

In practice, an object having a part which in cross-section corresponds in size and shape with the opening 9, such as a screwdriver having a square shank in cross-section, is inserted in said opening, or the wrench is engaged with such part or shank either from above or below, and the handle 10 is oscillated on the pivot 11 in a manner to cause that part of the cam-surface 12

which is on either side of the axial line of the handle, according to the direction in which it is desired to rotate said object, alternately to grip and release said work-holder. When the handle 10 is disposed in line with the plane common to the axes of the work-holder 8 and pivot 11, the cam-surface 12 is out of contact with said work-holder, and said handle is in inoperative or neutral position. As the handle 10 is moved in one direction or the other from neutral position the cam-surface 12 is caused to grip the work-holder 8, and to impart to said work-holder with the object engaged thereby, and to the head 1, a partial rotation in such direction; and when said handle is moved in the opposite direction back to neutral position, the head 1 is carried with it, said head rotating on the work-holder 8. These operations are repeated until the required amount of rotation has been given to the aforesaid object. Thus a step-by-step rotary motion is imparted to the object. When the step-by-step rotative movement is finished or completed the wrench is slipped off of the object or the latter is removed from the former.

We are aware that ratchet wrenches are old, and do not therefore seek to claim such a wrench broadly. Nevertheless, some modifications, in addition to those hereinbefore specially pointed out, may be made in our wrench without departing from the spirit of our invention or exceeding the scope of what is claimed.

What we claim as our invention, and desire to secure by Letters Patent, is—

1. As an improved article of manufacture, a ratchet wrench comprising a perforated head provided with lugs which are spaced apart, the perforation or opening in said head and the space between said lugs being in communication, a work-holder rotatable in said opening, means between the outer parallel surfaces of said head and work-holder to retain the latter in said opening, and a handle having a cam-surface and pivotally connected adjacent to said cam-surface with said lugs, with said cam-surface in operative position relative to said work-holder, the center of the arc of said cam-surface being back of the axis of the handle pivot toward the free end of the handle, and the distance between said axis and either end of said arc being sufficient to cause said cam-surface to grip and carry with it said work-holder, when said handle is swung in either direction.

2. The combination, in a ratchet wrench, with a perforated head provided with lugs which are spaced apart, the perforation or opening in said head and the space between said lugs being in communication, a pin immovably fixed in said head and projecting into said opening, and a work-holder rotat-

able in said opening, said work-holder being anitlarly grooved to receive the inner terminal of said pin, of a handle having a cam-surface and pivotally connected adjacent to said cam-surface with said lugs, with said cam-surface in operative position relative to said work-holder, the center of the arc of said cam-surface being back of the axis of the handle pivot toward the free end of the handle, and the distance between said axis and either end of said arc being sufficient to cause said cam-surface to grip and carry with it said work-holder when said handle is swung in either direction.

3. The combination, in a ratchet wrench, with a perforated head provided with lugs which are spaced apart, the perforation or opening in said head and the space between said lugs being in communication, a work-holder rotatable in said opening, said work-holder having therein an axial space for the work and a radial passage formed with a seat at the inner end, a ball in said passage, a spring in said passage between said ball and that part of said head which closes the outer end of the passage, said spring normally retaining said ball on its seat with a portion projecting into said axial space, whereby pressure is exerted on the work, when in said axial space, to prevent accidental separation of the parts, and means between the outer parallel surfaces of said head and work-holder to retain the latter in said opening, of a handle having a cam-surface and pivotally connected adjacent to said cam-surface with said lugs, with said cam-surface in operative position relative to said work-holder, the center of the arc of said cam-surface being back of the axis of the handle pivot toward the free end of the handle, and the distance between said axis and either end of said arc being sufficient to cause said cam-surface to grip and carry with it said work-holder when said handle is swung in either direction.

4. The combination, in a ratchet wrench, with a perforated head provided with lugs which are spaced apart, the perforation or opening in said head and the space between said lugs being in communication, a perforated work-holder rotatable in said opening, said work-holder having a peripheral groove therein, and means between the outer parallel surfaces of said head and work-holder, and engaging both head and work-holder, to retain the latter in said opening, of a handle having a cam-surface located in said space and operating in said groove, said handle adjacent to said cam-surface being pivotally connected with said lugs, the center of the arc of said cam-surface being back of the axis of the handle pivot toward the free end of the handle, and the distance between said axis and either end of said arc being sufficient to cause said cam-

surface to grip and carry with it said work-holder when said handle is swung in either direction.

5. The combination, in a ratchet wrench, with a perforated head provided with lugs which are spaced apart, the perforation or opening in said head and the space between said lugs being in communication, a pin immovably fixed in said head and projecting 10 into said opening, a work-holder rotatable in said opening, said work-holder being angularly grooved to receive the inner terminal of said pin, and having therein an axial space for the work and a radial passage 15 formed with a seat at the inner end, a ball in said passage, and a spring arranged in said passage between said ball and the part of the head which covers the outer end of the passage, which spring normally retains

said ball on its seat with a portion projecting into said axial space, whereby pressure is exerted on the work, when in said axial space, to prevent accidental separation of the parts, of a handle having a cam-surface located in said first-named space and operating in said groove against the work-holder, said handle adjacent to said cam-surface being pivotally connected with said lugs and the center of the arc of said cam-surface being back of the axis of the handle pivot 20 toward the free end of the handle, and the distance between said axis and either end of said arc being sufficient to cause said cam surface to grip and carry with it said work-holder when said handle is swung in 25 either direction.

CARL L. ERICSON.
WILLIAM ROBERTS.
